[57] CLAIM

The ornamental design for a pocketbook fastener, as shown and described.

DESCRIPTION

FIG. 1 is a perspective view of a pocketbook fastener according to my new design;

FIG. 2 is a perspective view thereof shown in an open position;

FIG. 3 is a side elevational view from the left thereof, the opposite side elevational view being a mirror image; FIG. 4 is a fragmentary front elevational view showing one side of the pocketbook fastener;

FIG. 5 is a fragmentary front elevational view of a pocketbook fastener, shown in a closed position;

FIG. 6 is a fragmentary bottom plan view thereof;

FIG. 7 is a fragmentary top plan view thereof; and, FIG. 8 is a fragmentary top plan view thereof with the fastener shown in an open position.

The broken line showing of the top of the pocketbook in FIGS. 1 and 2 is for illustrative purposes only and forms no part of the claimed design.
